(57) **CLAIM**

The ornamental design for a rotor arm of fishing reel, as shown and described.

DESCRIPTION

FIG. 1 is a top plan view of a rotor arm of fishing reel in accordance with my new design;

FIG. 2 is a front elevational view of the rotor arm of fishing reel in accordance with my new design;

FIG. 3 is a rear view of the rotor arm of fishing reel in accordance with my new design;

FIG. 4 is a left side view of the rotor arm of fishing reel in accordance with my new design;

FIG. 5 is a right side perspective view of the rotor arm of fishing reel in accordance with my new design.

FIG. 6 is a left side perspective view of the rotor arm of fishing reel in accordance with my new design; and,

FIG. 7 is a VII—VII cross sectional view of the rotor arm of fishing reel in accordance with my new design.

The broken line showing of environment (the remaining structure of the rotor arm of fishing reel) in the Figures is for illustrative purposes only and forms of the claimed design. Specifically, the inner surface of the rot arm of fishing reel is hereby disclaimed. The inner surface of the rotor arm of fishing reel does not form part of the claimed design.
